(57) **CLAIM**

The ornamental design for a mouthpiece, as shown and described.

DESCRIPTION

FIG. 1 is a top front perspective view of a first embodiment of a mouthpiece, showing my new design, shown in use with exemplifying environmental subject matter;

FIG. 2 is an enlarged top front perspective view thereof, with some exemplifying environmental subject matter removed;

FIG. 3 is a top rear perspective view thereof;

FIG. 4 is another top rear perspective view thereof;

FIG. 5 is a cross sectional side view thereof, taken in a direction of line 5-5 on FIG. 2;

FIG. 6 is another cross sectional side view thereof, taken in the direction of line 5-5 on FIG. 2, and in a position of use with additional exemplifying environmental subject matter; FIG. 7 is a front top perspective view of a second embodiment of a mouthpiece;

FIG. 8 is a front view thereof;

FIG. 9 is a right side view thereof, with the left side view being a mirror image thereof;

FIG. 10 is a top view thereof; and,

FIG. 11 is a bottom view thereof.

The broken lines are shown for the purpose of illustrating environmental structure and parts of the article that form no part of the claimed design.
